(57) **CLAIM**

The ornamental design for a razor package, as shown and described.

DESCRIPTION

FIG. 1 is a perspective view of the razor package of the present invention;

FIG. 2 is a front elevational view of the package of FIG. 1;

FIG. 3 is a rear elevational view of the package of FIG. 1;

FIG. 4 is a left side elevational view of the package of FIG. 1;

FIG. 5 is a right side elevational view of the package of FIG. 1;

FIG. 6 is a top plan view of the package of FIG. 1;

FIG. 7 is a bottom plan view of the package of FIG. 1;

FIG. 8 is a perspective view of another embodiment of a razor package of the present invention;

FIG. 9 is a front elevational view of the package of FIG. 8;

FIG. 10 is a rear elevational view of the package of FIG. 8;

FIG. 11 is a left side elevational view of the package of FIG. 8;

FIG. 12 is a right side elevational view of the package of FIG. 8;

FIG. 13 is a top plan view of the package of FIG. 8; and,

FIG. 14 is a bottom plan view of the package of FIG. 8;

The broken lines depict environmental subject matter only and form no part of the claimed design.
